UNITED STATES PATENT OFFICE.

GEORGE J. ZISCH, OF NEWARK, NEW JERSEY, ASSIGNOR TO NEWARK ENGINEERING AND REFRIGERATING COMPANY, OF NEWARK, NEW JERSEY, A CORPORATION OF NEW JERSEY.

PHONOGRAPH.

1,290,006.

Specification of Letters Patent. Patented Dec. 31, 1918.

Application filed February 12, 1917. Serial No. 148,029.

To all whom it may concern:

Be it known that I, GEORGE J. ZISCH, a subject of the Emperor of Germany, and a resident of Newark, county of Essex, and State of New Jersey, have invented certain new and useful Improvements in Phonographs, of which the following is a specification.

This invention relates to a phonograph which is adapted to be more easily operated, the parts for starting, stopping and regulating the speed of the motor being convenient in position and easy to operate.

The invention is further designed to provide a phonograph in which the operation of winding is made substantially noiseless and the starting and stopping of the motor is also made substantially noiseless, since the parts are kept in substantially close contact when the parts are running and also when they are stopped.

The invention is further designed to provide a phonograph in which an indicator is provided whereby the speed of the turntable, on which the record is supported, is indicated when the motor is running, the indicator being in view of the operator of the phonograph and being preferably arranged adjacent to a device whereby the speed can be regulated so that it will be evident to an observer when the turntable is revolving at normal speed or when its speed has been increased or decreased.

The invention is further designed to provide a phonograph in which starting and stopping devices are installed with operating buttons or studs which are convenient, easily operated and so connected that when one is pushed or depressed, the other is elevated or presented better for operation so that the stud to be next operated is always presented for operation.

A phonograph made according to my invention preferably has the starting and stopping devices, the indicator and the regulating means placed on the top of the motor casing adjacent to the turntable, and in my form of phonograph the starting and stopping devices are preferably connected directly with the motor, although this is not essential, such direct connection acting to relieve the noise incidental to the play between the turntable and the spindle on which it is mounted when a brake is applied to the

turntable, and it furthermore permits a more rigid and firm attachment of the turntable to the spindle on which it is mounted, and it can be located more closely to the top of the phonograph, since it is not necessary to provide space underneath it for the establishment of a brake.

The invention is illustrated in the accompanying drawings in which one form of my invention is illustrated, and in the several figures of which corresponding reference numerals are employed to indicate corresponding parts.

In said drawings, Figure 1 is a bottom view of the motor, the top of the phonograph casing and the turntable being broken away, this view also showing the connection between the motor and the indicating, regulating and starting and stopping devices. Fig. 2 is a section on line 2-2, in Fig. 3. Fig. 3 is a face view of a bearing and of a locking attachment to prevent reverse rotation of the arbor by means of which the springs and the motor are wound. Fig. 4 is a front view of the construction illustrated in Fig. 1 with part of the top of the casing broken away to more clearly indicate some of the parts, and Fig. 5 is a top view of the motor casing showing the starting and stopping, the regulating and the indicating means assembled in substantially one location on the casing. Fig. 6 is a section on line 6-6, in Fig. 5, and Fig. 7 is a detail of the yielding means for locking one of the studs of the starting and stopping devices.

The particular type of phonograph casing is not essential and it is not fully illustrated in the drawings in this case, it being necessary only to show the top part or plate 10 which forms the cover part of the motor casing, and the motor is secured in the casing 90 usually by suspending it from the under face of this cover 10, in the form shown the motor having a frame which is fastened by means of bolts 11 and nuts 12 to the part 10, the motor being driven in any preferred way, 100 but the motor is illustrated as a spring motor, the barrels 13 inclosing the springs and these springs, when under a tension and released, impart motion to a gear 14 which transmits power through an intermediate system of 105 driving to a spindle 15 on which the turntable 16 is mounted, the turntable 16 being used to support a disk record, it being under-

stood, of course, that proper changes in the support of the record can be provided if the record is a cylinder record. In the form shown the spindle 15 is provided with a bevel gear 16 which is in mesh with the bevel gear 17 and is on the same shaft and rotates with a spur gear 18 which is in mesh with the gear 14, and the spindle 15 has a worm gear 19 thereon which is in mesh with a worm 20 on the end of a governor shaft 21, which governor shaft is supported between the bearings 22 and 23 of the motor frame 24. The governor shaft 21 is provided with a fixed collar 25, that is, the collar rotates with the shaft 21 and is held against sliding on the shaft 21, the governor being provided with a sliding member which consists of a sleeve 26 having a shoulder 27 thereon and having a disk 28. The sleeve 26 and collar 25 are connected by springs 29 on which the governor weights 30 are fastened so that when the governor is rotating, the centrifugal force of the weights pulls the shoulder 27, the sleeve 26 and the disk 28, these parts being integral and sliding together and being preferably mounted so as to slide on a key or feather 31 so as to relieve the springs 29 of torsional strain. The disk 28 is used for indicating and also for regulating the speed of the governor, thus in turn regulating the speed of the turntable and of the motor. The means for limiting the movement of the disk 28 along the shaft 21 is utilized for regulating the speed, and a yielding means, pushed by the disk 28 when it moves, is used to indicate the speed, these elements being grouped, preferably, along with other manually operable parts, so as to make them convenient for use.

In the form shown the speed regulating device comprises a lever 32 which is pivoted to the bearing 23 and has on one end a block 34 adapted to be engaged by the disk, this block being usually made of a soft material, such as felt, and is frictionally engaged by the disk 28 when the motor is in operation, but it is usually kept lubricated in order to not interfere seriously with the smooth operation of the motor. The opposite end of the lever 32 is in engagement with the end of a screw 35, the end of the lever 32 being forked as at 32' and preferably arranged between collars so that it is pushed up and down as the screw is operated. The screw-threads 36 of the screw 35 travel in the screw-threaded barrel 37, which barrel is fastened to a plate 38. The upper end of the screw 35 projects above the top of the cabinet as at 39 and is provided with a finger-piece 40 by means of which it can be turned. To permit the operation and installation of this adjusting screw, and also for other associated devices, the top 10 of the casing is cut away as at 41 and provided with a cover plate 42 of suitable design.

65 To indicate the speed of the motor I

provide a suitable dial on the plate 38, this dial being indicated at 43 in Fig. 5. The dial may be provided with a glass cover 44 to prevent accumulation of dust on the dial. Suitably supported, and in the drawing being shown supported on the under side of the plate 38, is a bracket 45 which supports as indicator stem 46, the screw 47 supporting the indicator stem at the bottom, the stem having at its top a suitable pointer 48 which registers on the index plate 43 the speed at which the turntable 16 is rotating, this indicating usually being done by marks showing the number of revolutions per minute, the average machine having a normal revolution of 78 revolutions per minute which can be increased or decreased if desired to change the tempo of the reproduction. The indicator stem is yieldingly moved in one direction by a coiled spring 49 which is fastened at one end to the bracket 45 and at the other end to the stem, and acts to return the indicator hand to zero when the machine stops, but is not heavy enough to resist easy operation of the device when the machine is running. The indicator stem is provided with a collar 50 held in place by suitable means, such as a screw 51, and is provided with an eye 52 to which is pivoted a bar 53 which is in turn fastened to one end of a lever 54, such pivotal connection being shown at 55, the lever being pivoted intermediate of its ends, as at 56, to a suitable standard or post 57 and is provided on its other end with an engaging element 58, in the drawings this consisting of a pin which operates against the same face of the disk 28 as does the block 34, and is thus kept lubricated, and as the disk moves along the governor shaft 21, the stud or pin 58 is also moved, being held lightly in contact with the disk by the action of the spring 49. A means for stopping and starting the motor is provided, and for this purpose I utilize two buttons 59 and 60 which project up through the cover plate 42, in the preferred form of machine, in order to properly and conveniently group the different adjusting and regulating members. The buttons 59 and 60 are arranged on pins 61 and 62, respectively, these pins sliding through sleeves 63 and 64, the ends of the pins engaging a lever 65, the lever being adapted to rock as it is pivoted intermediate of its ends, as at 66, to a post 67. Proper locking means are provided for holding the buttons in two positions, as it will be evident that if one is pressed down the other is pushed up, and the one that is pushed up and is more accessible for use is the button 62 next to be operated in the alternate stopping and starting of the machine.

The pin 62 has a spring 68 abutting against the sleeve 64 and also against a shoulder or washer 69 on the stem, and a

second spring 70 is arranged so that it is under a tension, one way of doing this being by bending the spring around the sleeves 63 and 64, as will be clearly evident from Fig. 5. 1. The sleeve 63 is cut away as is shown more particularly in Fig. 7, this cut-away part 71 permitting the end of the spring 70 to engage the recessed part 72 in the pin 61. When the button 59 is pushed down as 10 in Fig. 6 the spring snaps into the cut-away part or annular recess 72 and holds the lever 65 down against the influence of the spring 68, but when the button 60 is pressed, the force exerted is sufficient to push the 15 pin 61 up so as to force the end of the spring 70 out of the depressed part 72, and the spring 68 is then free to hold the pin 62 down and the pin 61 up, which are the positions opposite to those shown in Fig. 6. 20 The rocking lever 65 is suitably connected with a starting and stopping means, in the form shown this comprising a lever 73 which has one end 74 fitting in an eye 75 of the lever 65 and is pivoted, as at 76, to the bearing 25 28 and is provided with a block 77 which is forced against a disk 78 fastened to the governor shaft 21, this disk being fastened, such as by screws 79, so that it cannot slide, and when the block 77 is 30 pressed against the disk 78 it acts as a brake and stops the rotation of the disk, and consequently the governor, the motor and the turntable are also stopped.

It will be evident that the operation of 35 the device is simple, since when the button 59 is pressed down and locked by the spring 70, it forces, through the medium of the lever 73, the block 77 against the disk 78, and when the machine is to be started, 40 the button 60 is pushed down, the spring 70 is displaced, the spring 68 is made operative, which rocks the lever 65, and the lever 73 is in turn swung on its pivot to pull the block 77 away from 45 the disk 78 and the brake is released. As the governor begins to rotate, the disk 28 is pulled so as to push on the stud 58 and thus, through the connecting mechanism, 50 swings the index hand 48 so that the person using the machine can, when necessary, ascertain the speed at which the turntable is 55 rotating. If the speed of the machine is to be changed, the finger-piece 40 is rotated, and it in turn, through connecting mechanism 55 above described, changes the position of the block 34 so as to shift the position of the disk 28 which not only changes the speed of the machine, but also causes a corresponding indication on the indicator 43 of the 60 amount of change of the speed.

The device is simple to operate and it is substantially noiseless, and furthermore, it requires but little effort or motion to manipulate the stopping and starting devices. 65 The brake operating against the disk on the

governor shaft keeps the tension tight against the worm 20, by means of which the governor is operated, both when the machine is at rest and when it starts, and there is thus no possibility of any "backlashing" 70 of gearing, or similar looseness which will make a noise when the machine is started or stopped. This means of stopping is also preferable over a brake acting against the turntable, since it does not cause any noise 75 due to lost motion when such stopping occurs, since brakes on turntables usually have a noise resulting from this looseness when the brake is applied to the turntable, and the stem on which the turntable is mounted 80 has a slight motion in relation to the turntable and this causes a click or slight thud.

As a further means of eliminating noise in the phonograph, I provide the arbor 80 on the spring barrels with a locking means 85 which does not click when the machine is wound up. The arbor is provided, as is usual in machines of this kind, with a removable crank, the shank 81 of which fits into a screw-threaded recess 82 at the end of the 90 arbor. A bracket 83 is placed adjacent to the end of the arbor 80, which is provided at this end with an enlargement 84 having a concentric exterior. The bracket 83 has an eccentric interior face 85, and between the 95 exterior face of the enlarged part 84 and the face 85 is a roller 86 which being forced, by reverse rotation of the arbor 80, between the converging surfaces 84 and 85, binds the arbor against further reverse rotation, the 100 binding action of the roller 86 upon such reverse rotation being insured by the spring 87 encircling a pin 88 having its inner end provided with a small shoe 89 which engages the roller 86 to force it into position. When, 105 however, the arbor is rotated to wind up the springs in the motor, the roller 86 rotates, since the tendency of the friction thereon is to move it against the light spring 87 and into the larger part of the recess between 110 the outer face 84 and the inner face 85 of the arbor and bracket respectively. The absence of any pawls or ratchets, or any other clicking parts, provides for a noiseless winding of the motor. 115

Having thus described my invention, I claim:

1. A phonograph comprising a motor, a brake on the motor, a lever for operating the brake, a sliding stem for starting the motor, a sliding stem for stopping the motor, a rocking lever with which said stems are engaged whereby when one is pushed the other is raised, said rocking lever and the lever being connected, a spring encircling one of 120 said stems, and yielding means on the other of said stems to lock the stems against the influence of the spring. 125

2. A phonograph comprising a motor, a brake on the motor, a lever for operating the 130

brake, a sliding stem for starting the motor, a sliding stem for stopping the motor, a rocking lever with which said stems are engaged whereby when one is pushed the other 5 is raised, said rocking lever and the lever being connected, a spring encircling one of said stems, a stud on which the rocking lever is pivoted, a spring bearing on the stud and

having its other end adapted to engage one of said stems, said stem having a recess in 10 which the last mentioned spring can be partially seated.

In testimony that I claim the foregoing I hereto set my hand, this 10th day of February, 1917.

GEORGE J. ZISCH.
